UNITED STATES PATENT OFFICE.

A. J. ELLIOTT, OF MASON CITY, IOWA.

CAR-COUPING.

SPECIFICATION forming part of Letters Patent No. 359,599, dated March 22, 1887.

Application filed May 19, 1886. Serial No. 202,692. (No model.)

To all whom it may concern:

Be it known that I, A. J. ELLIOTT, of Mason City, in the county of Cerro Gordo and State of Iowa, have invented an Improved Car-Coupling, of which the following is a specification.

The invention will first be described in connection with the drawings, and then pointed out in the claims.

10 Figure 1 of the drawings is a plan view; Fig. 2, a longitudinal section; Fig. 3, a front elevation, and Fig. 4, a detail perspective view.

In the drawings, A A represent two draw-heads, in which are the cavities a a and the 15 mouth or front opening, a'.

a' is the bottom incline, up which the link is guided into the draw-head, and at the upper part of this incline is a median groove, a³.

B is the coupler, which is end-pivoted in 20 the front of the draw-head at b in the draw-head groove a⁴, while the end b' falls into the groove a⁵, both ends being thus held in grooves to prevent the possibility of lateral displacement. The end b' has on the bottom of groove 25 a bearing in a diagonal line or plane with the pivot b, thus giving a good purchase to the draft.

b² is a hollow cap, which receives the end of link C and prevents it from swinging laterally, 30 said link being thus always kept in a straight line with the longitudinal axis of the car, except in rounding a curve, when a minimum of departure therefrom is obtained.

On the back of the coupler B, I fasten an 35 eye, b⁴, connecting this by a chain, D, with a crank, e, on the shaft E, which has its bearings so arranged in the ears a⁶ a⁷ that the crank

will turn flat, or nearly so, on the top of draw-head. In this position it holds up the coupler B, so that the link can be drawn out and 40 the cars uncoupled, and the coupler will continue up until the shaft is turned back a half or a little more than a half revolution. The chain passes through a longitudinally - oblong hole or slot, a⁸, in the top of the draw-head, wherein it is allowed the necessary play back and forward.

The shaft E may have an arm, e', connecting with lifting mechanism extending to the top of the car, or it may be turned by crank-arms 50 e² e² on the sides.

Having thus described all that is necessary to a full understanding of my invention, what I claim as new, and desire to protect by Letters Patent, is—

1. The combination, with a draw-head having the grooves a³ a⁴, of the coupler B, pivoted at b in the groove a⁴, and resting diagonally in the groove a⁵, as and for the purpose set forth.

2. The coupler B, made with a hollow cap, b², in rear of the draft end b', to receive the end of link, as and for the purpose specified.

3. The combination, with a pivoted coupler, a chain, and a draw-head having the hole a⁸, 65 of the shaft E, having the crank e, and arranged in bearings, so that when the shaft is turned over the crank will rest on the top of draw-head and hold up the coupler, as described.

A. J. ELLIOTT.
